UNITED STATES PATENT OFFICE.

JOSEPH F. MOELLER, OF CHICAGO, ILLINOIS, ASSIGNOR TO WATERMAN W. PORTER, OF CHICAGO, ILLINOIS.

CIGARETTE CASE.

1,408,464.

Specification of Letters Patent. Patented Mar. 7, 1922.

Application filed February 16, 1920. Serial No. 359,022.

To all whom it may concern:

Be it known that I, JOSEPH F. MOELLER, a citizen of the United States, residing at Chicago, in the county of Cook and State 5 of Illinois, have invented certain new and useful Improvements in Cigarette Cases, of which the following is a specification.

This invention relates to cigarette cases of that type wherein a row of cigarettes disposed side by side within the case is subjected laterally to the pressure of a spring actuated follower, and the foremost cigarette of the row is partially ejected endwise through a delivery opening in one side wall 10 of the case by means of a sliding ejector, the next cigarette of the row automatically taking its place as soon as the foremost cigarette is withdrawn. Cigarette cases of this general type are in extensive use, and 15 not only form a handy and convenient dispenser for the goods as they are desired for use, but also protect the cigarettes from dirt and injury while being carried about.

The principal object of the present invention is to provide a simple and improved cigarette case of the character referred to, and more particularly to provide an improved construction of spring pressed follower heads and guides, and an improved 20 construction of ejector slide and guiding means therefor.

My invention, in a practical and preferred embodiment thereof, is illustrated in the accompanying drawing, in which—

35 Fig. 1 is a top plan view of the case in closed condition showing by dotted lines a portion of the foremost cigarette projecting from the delivery opening of the case;

40 Fig. 2 is an edge elevation as viewed from the right of Fig. 1;

Fig. 3 is a horizontal section taken in a plane a slight distance below the plane of the lid or cover;

45 Fig. 4 is an enlarged detail in section showing parts adjacent to the delivery opening; and,

Fig. 5 is a section taken on the line 5—5 of Fig. 3 viewed in the direction indicated by the arrows.

50 Referring to the drawing, the rectangular box comprises the bottom plate 6, side edge walls 7 and 8, end edge walls 9 and 10, and lid or cover 11 hinged to the end edge wall 9 at 12.

55 Mounted on the inner sides of the side

edge walls 7 and 8 parallel with and spaced slightly from the latter are a pair of guide rods 13, and through the side edge wall 7, opposite one end of the guide rod 13, is a delivery opening 14.

Within the box is a hollow follower head of U-shape in cross section comprising, as most clearly shown in Fig. 5, top and bottom walls 15 and 16 and a front or face wall 17. End portions of the face wall 17 are countersunk, as shown at 17' in Figs. 3 and 4, and in these countersunk ends 17' are holes 18 by which the follower head is slidably engaged with the guide rods 13. These holes 18 are sufficiently larger in diameter than the guide rods 13 to permit the follower head to cant or tilt endwise to a limited extent sufficient to enable it to follow any tilting tendency of the rearmost cigarette with which it is in contact; and this tilting or canting capacity is further promoted by cutting away the ends of the follower head rearwardly, as shown at 19 in Figs. 3 and 4, the length of the follower head being approximately equal to the internal width of the box body. The 65 follower head is normally urged forwardly by a light zig-zag spring 20 bearing at one end against the end edge wall 10 and at its other end against the rear side of the face 70 wall 17 of the follower head.

85 Cigarettes, especially when subjected to lateral pressure, are rarely of uniform thickness or diameter from end to end, so that, when a row of cigarettes is placed within the box, as shown in Fig. 3, and the pressure of 90 the follower head is applied to the rearmost cigarette, the latter will almost always lie in a slightly endwise tilted or canted position; and I have found that it is advantageous in a delivery box of this character to 95 give the follower head sufficient end play in or on its guiding means to permit it to automatically follow such tilting or canting of the rearmost cigarette as may occur, so as to bear with equal pressure at all points 100 along the length of the latter. This is effected by the play between the holes 18 and the guiding rods 13 and by the rearward rounding or cutting away of the ends of the follower head, as shown at 19.

105 It will be observed by reference to Fig. 5, in which the box appears up-side down in transverse section, that the forward end of the spring 20 bears against the face wall 17 of the follower head above the center of 110

the latter. This tends to tilt or cant the follower head slightly toward the bottom of the box, so that the push upon the row of cigarettes is slightly above the central or median lines thereof. This effectively prevents the row of cigarettes from springing or buckling up before the lid or cover is closed, and does away with the necessity of a spring finger that is sometimes employed to hold the row of cigarettes level until the lid is closed.

The end edge wall 9 is formed with a longitudinal slot 21, and parallel with and spaced inwardly from the wall 9 is a partition wall 22 that likewise has a longitudinal slot 23. The partition wall 22, as best shown in Fig. 5, is preferably curved transversely and is formed with channel guides 24 on its longitudinal margins. These channel guides receive the longitudinal edges of an ejector slide 25 that is transversely curved to fit the partition wall 22, and at its lower end has a transversely extending foot 26 that normally lies beneath or behind the end of the foremost cigarette that is remote from the delivery opening 14. To the ejector slide 25 is soldered or otherwise secured the shank 27 of a button 28, said shank passing through the slot 23 of the partition wall 22 and the slot 21 of the end wall 9. On the back side of the ejector slide 25 is secured a strip 29 carrying a pin 30 to which is anchored one end of a tensile spring 31, the lower end of said spring being anchored to a lug or pin 32 on the end wall 9, the function of this spring being to return the ejector slide to its normal idle position shown in Fig. 3.

The manner of use is readily apparent from the foregoing description. The box having been loaded with cigarettes, the latter are successively ejected to a position, shown by dotted lines in Figs. 1 and 2, in which they may be readily withdrawn by the thumb and finger, by merely pushing the button 28 from the full-line position shown in Figs. 1 and 2 to the dotted line position therein shown, the follower instantly advancing the entire row of cigarettes, as the foremost cigarette is withdrawn. With the described construction of follower and follower guides, the tendency of the follower to stick, noticeable in some constructions now in use, is entirely obviated, as is also the tendency of the cigarettes to buckle upwardly. Furthermore, the described construction of partition wall and ejector slide eliminates all danger of breaking or cracking the wrappers of the cigarettes in the operation of ejecting the latter.

I claim—

1. In a cigarette case, the combination of a rectangular box adapted to contain a row of cigarettes arranged side by side and having a delivery opening in one side edge

thereof, a follower head slidably mounted in said case, a spring engaging said head above its longitudinal center line, thereby tending to prevent buckling of the cigarettes, and an ejector for forcing the foremost cigarette of the row endwise through 70 said opening.

2. In a cigarette case, the combination of a rectangular box adapted to contain a row of cigarettes arranged side by side and having a delivery opening in one side edge 75 thereof, a pair of guide-rods mounted on the inner sides of the side edges of said box, a spring-pressed follower head formed with holes in its ends by which it is slidably mounted on said guide-rods, said holes being sufficiently larger than said rods to permit a limited canting movement of said follower-head, and an ejector for forcing the foremost cigarette of the row endwise 80 through said opening.

3. In a cigarette case, the combination of a rectangular box adapted to contain a row of cigarettes arranged side by side and having a delivery opening in one side 90 edge thereof, a pair of guide-rods mounted on the inner sides of the side edges of said box, a hollow follower-head of U-shape in cross section, the face of said follower-head having countersunk end portions apertured 95 to engage with said guide-rods, the apertures of said end portions being sufficiently larger than said rods to allow a limited canting movement of said follower-head, a spring urging said follower-head forwardly, 100 and an ejector for forcing the foremost cigarette of the row endwise through said opening.

4. In a cigarette case, the combination of a rectangular box adapted to contain a row of cigarettes arranged side by side and having a delivery opening in one side edge 105 thereof, a pair of guide-rods mounted on the inner sides of the side edges of said box, a hollow follower-head of U-shape in cross- 110 section of a length approximately equal to the internal width of said box and formed with rearwardly cut-away ends, the face of said follower-head having countersunk 115 end portions apertured to engage with said guide-rods, the apertures of said end portions being sufficiently larger than said rods to allow a limited canting movement of said follower-head, a spring bearing against the rear side of the face of said follower head 120 in a manner to normally tilt the same slightly toward the bottom wall of the box, and an ejector for forcing the foremost cigarette of the row through said opening.

5. In a cigarette case, the combination of 125 a rectangular box adapted to hold a row of cigarettes arranged side by side and formed with a slotted end wall and a delivery opening in one side wall adjacent to said slotted end wall, a slotted partition wall 130

- mounted inwardly of and parallel with said slotted end wall and formed with channel guides on its longitudinal margins, an ejector slide slidably engaged with the channel guides of said partition wall and having a foot at one end, a button lying outside said slotted end wall and having a shank extending through the slot of the latter and the slot of said partition plate and attached to said ejector slide, and a spring-pressed follower in said box urging the foremost cigarette against said partition wall.
6. In a cigarette case, the combination of a rectangular box adapted to hold a row of cigarettes arranged side by side and formed with a slotted end wall and a delivery opening in one side wall adjacent to said slotted end wall, a slotted partition wall mounted inwardly of and parallel with said slotted end wall and formed with channel guides on its longitudinal margins, an ejector slide slidably engaged with the channel guides of said partition wall and having a foot at one end, a button lying outside said slotted end wall and having a shank extending through the slot of the latter and the slot of said partition plate and attached to said ejector slide, a slide-returning spring located in the space between said end wall and partition wall, and a spring-pressed follower in said box urging the foremost cigarette against said partition wall.

JOSEPH F. MOELLER.
